R. HOFSTETTER

ACETYLENE TORCH

Filed July 11, 1921

Inventor
Robert Hofstetter
By Arthur A. Durand
Attest.

UNITED STATES PATENT OFFICE.

ROBERT HOFSTETTER, OF CHICAGO, ILLINOIS, ASSIGNOR, BY MESNE ASSIGNMENTS,
TO THERMALENE GAS CORPORATION, A CORPORATION OF ILLINOIS.

ACETYLENE TORCH.

Application filed July 11, 1921. Serial No. 483,711.

To all whom it may concern:

Be it known that I, ROBERT HOFSTETTER, a citizen of the United States, and a resident of Chicago, county of Cook, State of Illinois, have invented a certain new and useful Improvement in Acetylene Torches, of which the following is a specification.

This invention relates to acetylene torches of that kind in which oxygen and acetylene gas are mixed in the proper proportions and discharged through a nozzle to produce the flame which can be employed in the usual and well known manner, for various purposes, such as cutting iron or steel, or for similar purposes.

Generally stated, the object of the invention is to provide a novel and improved construction and arrangement whereby two or more nozzles for producing flames of different sizes, depending upon the size of the jet or flame required for any particular purpose, may be employed interchangeably in connection with the same torch, in a manner that insures not only the required volume of mixture for each different nozzle, but also in a manner that insures the correct proportions of the mixture, whereby the proportions in which the oxygen and the acetylene gas are mixed remain fixed and are not changed, regardless of the volume of the mixture and the size of the flame produced by the different nozzles which have, of course, discharge passages or outlets of different sizes to enable the user to substitute one nozzle for another, on the head of the torch, thereby to change the volume or size of the jet or flame which is required to do the work.

To these and other useful ends the invention consists in matters hereinafter set forth and claimed and shown in the accompanying drawings in which—

Figure 1 is a side elevation of a torch embodying the principles of the invention.

Figure 2 is an enlarged longitudinal section of the head and nozzle of the torch.

Figure 3 is an end view of the mixer included in the head of the torch.

Figure 4 is a longitudinal section of said mixer on line 4—4 in Figure 3.

Figure 5 shows an inner end portion of another nozzle in which the passage is somewhat larger than the one shown in Figure 2.

Figure 6 is a similar view showing said passage still larger, and illustrating how the

inner end portion of the nozzle is made shorter as the discharge passage of the nozzle grows larger, in the set or plurality or series of interchangeable nozzles provided with the torch.

As thus illustrated, the invention comprises a handle 1 to which are connected the tubes 2 and 3 employed respectively, for supplying the oxygen and the acetylene gas for the head 4 of the torch. Valves 5 and 6 are provided to control respectively, the flow of oxygen and acetylene gas through the handle and through said tubes, in the usual and well known manner.

The head 4 of the torch, to which the invention more particularly relates, has a screw threaded cap 7 which screws upon the head to hold the nozzle 8 in position as shown. Said nozzle has an inner end portion 9 in the form of a small tube, and this tube extends into the mixer 10 which is beveled at 11 and 12 to engage the bevels 13 and 14 formed on the interior surface of the head. Between these two bevels is a cylindrical chamber 15, and at the end of said mixer there is a smaller chamber 16, as shown in Figure 2, and with this construction it will be seen that the pipe 2 communicates with the chamber 16, while the pipe 3 communicates with the chamber 15, thereby to supply the oxygen and the acetylene gas to the mixer. Said mixer has a central bore 17 for the tube 9, and has three smaller bores 18, 19, and 20 of different lengths. The bore 18 is connected by transverse passages 21 with the bore 17; the bore 19 is connected to the bore 17 by transverse passages 22; and the bore 20 is connected to the bore 17 by transverse passages 23; and it will be seen that all of these transverse passages have continuations or extensions thereof in alignment therewith at the other side of the bore 17 in order to communicate with the chamber 15, these transverse passages being drilled transversely through the mixer 10 until they terminate in their respective or allotted bores 18, 19, and 20, whereby each said continuation is spaced a distance from its allotted passage in the manner shown and described. Thus the passages 21, 22, and 23 are arranged in groups, each group being at a different point in the length of the mixer. With this construction, it is obvious that by varying the length of the tube 9 which is the inner end of the nozzle, either a

greater or a less number of these transverse passages drilled through the mixer will be left open to communicate with the bore 17, thus controlling the supply of each fluid to the mixer and varying the volume of the mixture to be discharged by the nozzle. The mixer has a plurality of primary oxygen inlets 18, 19 and 20 and a plurality of acetylene inlets; and each primary oxygen inlet has a plurality of secondary or final inlets which are diametrically opposite and in alinement with said acetylene inlets. As shown in Figure 2 only one transverse passage 21 is open to discharge oxygen into the bore 17, from the chamber 16, and to discharge acetylene gas from the chamber 15 into the bore 17 of the mixer. However, a tube 9 a little shorter than the one shown in Figure 2 would leave another passage 21 open, thus increasing the volume of the mixture. Figures 5 and 6 show tubes 9 which are still shorter and which, therefore, will leave open an additional number of said transverse passages in the mixer, inasmuch as the bore of the tube is greater in Figure 5 than it is in Figure 2, and is greater in Figure 6 than it is in Figure 5, and such increased diameter of the bore of the nozzle requires an increased supply of mixture of oxygen and acetylene gas. Therefore, in accordance with the principles of the invention, each nozzle has either a longer or a shorter inner end portion or tube, and the mixer has a plurality of transverse passages which co-operate with the said tubes of different lengths to automatically vary or change the volume of the mixture in accordance with the size of the bore of the nozzle to be used for the desired work.

It will be understood, of course, that the invention is not limited to any particular use, or to any particular gases, inasmuch as hydrogen gas or Blau gas or Pintsch gas, and several others could be readily substituted for acetylene gas, for different kinds of work, should such be found necessary or desirable. Therefore, by the use of the term acetylene in the specification and claims, it will be understood that what is meant is that the torch is adapted to use acetylene gas, or any of the equivalents or substitutes therefor.

It will be seen that the mixer 10 has a plurality of fluid inlets 18, 19 and 20, and that each inlet has a group of short transverse inlets allotted thereto, the longitudinal inlet 18 or 19 or 20 constituting the primary inlet, and the short and smaller openings constituting the secondary inlets. The primary inlets 18, 19 and 20 are all of different lengths, so that the groups of secondary inlets are disposed at different points in the length of the mixer, the oxygen being admitted to the mixer from the chamber 16 as previously described. The transverse inlets

for the acetylene, whereby the acetylene passes from the chamber 15 into the mixer, are simply continuations of the oxygen inlets, these continuations being spaced from the oxygen inlets a distance equal to the chamber of the bore 17 previously described. Thus the acetylene inlets are disposed in groups, and it is not only true that the members in each group are disposed at different points in the length of the mixer, but it is also true that the different groups themselves are disposed at different points in the length of the mixer, as well as different points circumferentially thereof, it being observed that the three oxygen inlets 18, 19 and 20 are arranged at equidistant points in the circumference of the mixer.

What I claim as my invention is:

1. In an acetylene torch, the combination of a head having a mixer therein for mixing one fluid with another, and a nozzle having an inner end portion to receive the mixture from said mixer, to produce a discharge of the desired character from the outer end of the nozzle, said mixer having means whereby the supply of each fluid thereto is controlled and the volume of said discharge is determined by the length of said inner end portion of the nozzle.
2. A structure as specified in claim 1, said means comprising a plurality of transverse passages in the mixer, disposed at different points in the length thereof, and said inner end portion being adapted to leave open a greater or a less number of said passages, depending upon the length of said inner end portion.
3. A structure as specified in claim 1, said means comprising a plurality of longitudinal bores of different lengths, a central and larger bore, and a plurality of transverse passages connecting each smaller bore to said larger bore, with continuations of said transverse passages extending in alinement therewith from the central bore to the outer sides of the mixer, so that the inlets for said transverse passages are located at different points in the length of said mixer, an oxygen chamber communicating with said smaller bores and an acetylene gas chamber communicating with the outer ends of said transverse passages whereby the oxygen and the gas are mixed in said larger bore in the desired proportions and in volume according to the number of transverse passages left open by said inner end portion, which latter extends into said larger bore a distance to leave open the desired number of said transverse passages necessary to produce the volume of mixture required by the nozzle.

4. A structure as specified in claim 1, said mixer comprising a separate element having a central bore to receive said inner end portion, and having beveled portions at the opposite ends thereof, with a cylindric space

between said bevels, said head having means for engaging said bevels, and a cap to draw the nozzle into place and to thereby force said mixer into position to form tight joints where said bevels occur.

5. In an acetylene torch, a mixer therein for mixing a plurality of fluids before the final discharge thereof from the torch, having a plurality of inlets of different lengths for one fluid extending longitudinally thereof, with one or more transverse inlets extending inwardly from each longitudinal inlet, whereby these last mentioned or final inlets are disposed at different points in the length of the mixer, as well as at different points circumferentially thereof, inlet means for admitting another of said fluids to the mixer, and means extending into the mixer to discharge the mixture therefrom and serving to determine the volume of the discharge by closing one or more of said final inlets.

6. A structure as specified in claim 5, said inlet means comprising other transverse inlets disposed in alinement with said final inlets. 25

7. A structure as specified in claim 5, said inlet means comprising other transverse inlets to admit the other fluid.

8. A structure as specified in claim 5, said inlet means comprising transversely disposed inlets which are also controlled by said means extending into the mixer. 30

9. In an acetylene torch, a mixer having a plurality of inlets for an oxidizing fluid, 35 as well as a plurality of inlets for a combustible fluid, whereby to produce the desired mixture, and discharging means extending into the mixer to close one or more of the inlets for each fluid to control the 40 volume of the discharge without varying the proportions of the mixture.

ROBERT HOFSTETTER.
